PROCESS FOR FIXEDLY LOCATING A MEMBER IN A BORE

Paul B. Shultz and Daniel Tuitman, St. Joseph, Mich., assignors to The Bendix Corporation, St. Joseph, Mich., a corporation of Delaware

Filed Jan. 22, 1962, Ser. No. 167,646
7 Claims. (Cl. 29—522)

The invention disclosed herein relates to a process for securing two members together.

More particularly, the invention relates to a process for fixedly locating a member in a bore.

An object of the invention is to provide a process for securing a member to the wall of a wheel cylinder.

Another object of the invention is to provide a process for securing an element to the wall of a bore of a body member wherein pressure is applied to one face of the element to expand or swedge the outer periphery of the element into engagement with the wall while the element is supported by support means other than that forming the finished assembly.

A still further object of the invention is to provide a process for securing an element to the wall of a bore within a body member wherein pressure is applied to one face of the element to expand or swedge the outer periphery of the element into engagement with the wall while the other face of the element is supported about its outer periphery by a stationary ram and at its central portion by a yieldable take-up ram.

Other objects and features of the invention will become apparent from a consideration of the following description, which proceeds with reference to the accompanying drawings, wherein:

FIGURE 1 illustrates a baffle member secured to the wall of a bore of a wheel cylinder;

FIGURE 2 illustrates a plan view of the baffle member;

FIGURE 3 illustrates a section taken on line 3—3 of FIGURE 2;

FIGURE 4 illustrates the position of the rams and baffle member prior to application of pressure to secure the baffle member to the wall of the bore of a wheel cylinder; and

FIGURE 5 illustrates the position of the rams and baffle member after pressure has been applied to secure the baffle member to the wall of the bore of the wheel cylinder.

With reference to FIGURE 1, there is illustrated a baffle member 10 secured into a groove 11 of a wall 12 of a bore in a wheel cylinder housing 14. The purpose of the baffle member is to retard movement of the secondary shoe toward the anchor pin to eliminate noise or "clunk". The baffle member 10 is located between the inlet port 39 of the wheel cylinder housing 14 and the piston 13 which is to be connected to a secondary shoe (not shown). The baffle has a small opening 26 therein which allows passage of oil from the chamber 15 to the chamber 17 and conversely. Upon application of the brake, oil will first pass from chamber 15 to chamber 17 to spread the shoes and as the secondary shoe is forced toward the anchor pin the baffle will act as a dashpot slowing the passage of oil from chamber 17 to chamber 15 and therefore the movement of piston 13 toward the center and movement of the secondary shoe toward the anchor pin. The invention relates to a process for securing the well known assembly of the baffle 10 and the wheel cylinder housing 14 together.

The baffle member 10 illustrated in FIGURES 2 and 3, has a central portion 16 axially offset from the outer periphery 18. A notch 20 is impressed in the baffle mem-

2

ber for registering with a corresponding notch 22 of a take-up ram 24 thereby locating the baffle member 10 radially relative to the take-up ram 24. The opening 26 is located on the annular surface 28 of the baffle member.

With reference to FIGURE 5, there is provided a stationary ram 30 surrounding a movable take-up ram 24 which is supported by a member of resilient material 34. A bracket 36 is connected to base 42 and is so shaped that the wheel cylinder housing 14 may be placed over the stationary and take-up rams in one radial position only and located axially with respect to the stationary ram. The boss 38 has been shown in simplified form omitting the inlet 40 and a bleed port for the purposes of clarity. The base 42 is mounted to a stationary structure.

In performing the process of securing the baffle member 10 to the groove 11 of the wheel cylinder housing 14, the baffle member 10 is placed on the take-up ram 24 and the stationary ram 30 with the notch 20 of the baffle member being matched with the notch 22 of the take-up ram 24. The baffle member 10 will have its inner face 44 of the central portion 16 and its inner face 46 of the annular surface 28 engaging the take-up ram 24 and will have the inner face 48 of its outer periphery 18 engaging the stationary ram 30. The wheel cylinder housing is then inserted over the stationary ram 30, take-up ram 24 and the baffle member 10 or another way of positioning the baffle and cylinder housing on the take-up and stationary rams would be to place the wheel cylinder housing over the stationary and take-up rams 30 and 24 respectively, and then insert the baffle member 10 through the opening 52 and place it on the stationary and take-up rams. The outer periphery 18 of the baffle member will take a position contiguous the groove 11 of the wall 12 and the opening 26 will be oriented correctly with respect to the wheel cylinder housing 14 due to the notch fitting 20, 22 of the baffle plate and the take-up ram and the radial and axial positioning of the wheel cylinder housing by the bracket 36. A driving ram 50 is inserted through the opening 52 of the housing 14 and brought into engagement with the baffle member 10. FIGURE 4 illustrates the positions of the baffle member, driving ram, take-up ram, stationary ram and groove prior to the application of pressure to the driving ram 50.

When pressure P is applied to the driving ram 50, the driving ram 50 presses the central and annular surface 16 and 28 of the baffle member against the take-up ram 24 compressing the resilient member 34 and at the same time applies force against the outer periphery 18 of the baffle member against the stationary ram 30 thereby expanding or swaging the outer periphery 18 into the annular groove 11 of the wall 12, as illustrated in FIGURE 5. It should be noted that the sole support for the baffle member during the application of force by the driving ram 50 are the driving and take-up rams which do not form any part of the wheel cylinder housing, or in other words do not form any part of the member to which the baffle member is secured.

It should be noted that this process need not necessarily be used in conjunction with a groove such as groove 11 of the housing 14 but could be used for swaging the outer periphery of the baffle member into a frictional fit with the wall of the bore 12. Furthermore, while the process has been demonstrated in connection with fixedly locating a baffle to a wheel cylinder, the process disclosed may be used where any member is to be secured to the bore of any body member.

It is intended that such revisions and variations of the invention, which incorporate the herein disclosed principles, as are reasonably to be expected on the part of

those skilled in the art will be included within the scope of the following claims.

We claim:

1. A process for securing two members together comprising the steps of: providing a body member having a bore therein whose longitudinal dimensions extend from one surface to another and providing a deformable member whose central portion is axially offset from its outer periphery; the portion of said deformable member located between said central portion and said outer periphery being inclined to the axis of said deformable member in a direction, extending from said central portion to said periphery, which is away from said axis; locating said deformable member in said bore with the outer periphery thereof contiguous the wall of said bore; applying pressure to said deformable member at the outer face thereof while yieldably supporting said central portion at the inner face and rigidly supporting the outer periphery of the inner face of said deformable member contiguous said wall by support means distinct from the body member thereby expanding the outer periphery of said deformable member into frictional fit with said bore.

2. A process for securing two members together comprising the steps of: providing a body member having a bore therein whose longitudinal dimensions extend from one surface to another, a groove in the wall of said bore; providing a deformable member whose central portion is axially offset from its outer periphery; the portion of said deformable member located between said central portion and said outer periphery being inclined to the axis of said deformable member in a direction, extending from said central portion to said periphery, which is away from said axis; locating said deformable member in said bore with the outer periphery thereof contiguous said groove; applying pressure to said deformable member at the outer face thereof while yieldably supporting said central portion at the inner face and rigidly supporting the outer periphery of the inner face of said deformable member contiguous said groove by support means distinct from the body member to expand the outer periphery of said deformable member into said groove.

3. A process for securing two members together comprising the steps of: providing a body member having a bore therein whose longitudinal dimensions extend from one surface to another and providing a deformable member whose central portion is axially offset from its outer periphery; the portion of said deformable member located between said central portion and said outer periphery being inclined to the axis of said deformable member in a direction, extending from said central portion to said periphery, which is away from said axis; locating said deformable member in said bore with the outer periphery thereof contiguous the wall of said bore; applying pressure to said deformable member at the outer face thereof while supporting said deformable member at the opposite face thereof by a stationary ram engaging the outer periphery of said deformable member and a yieldable take-up ram engaging the central portion thereby expanding the outer periphery of said deformable member into frictional fit with said bore.

4. A process for securing two members together comprising the steps of: providing a body member, said body member having a bore therein whose longitudinal dimensions extend from one surface to another, a groove in the wall of said bore; providing a deformable member whose central portion is axially offset from its outer periphery; the portion of said deformable member located between said central portion and said outer periphery being inclined to the axis of said deformable member in a direction, extending from said central portion to said periphery, which is away from said axis; locating said deformable member in said bore with the outer periphery thereof contiguous the wall of said bore; supporting said deformable member at the inner face thereof by a stationary ram engaging the outer periphery of said deformable

member and a yieldable ram engaging the central portion thereof, said deformable member being supported by said rams so said outer periphery will be contiguous said groove; applying pressure to the other face of the deformable member thereby expanding the outer periphery of said deformable member into said groove.

5. A process for securing two members together comprising the steps of: providing a body member having a bore therein whose longitudinal dimensions extend from one surface to another, and providing a deformable member whose central portion is axially offset from its outer periphery; the portion of said deformable member located between said central portion and said outer periphery being inclined to the axis of said deformable member in a direction, extending from said central portion to said periphery, which is away from said axis; providing a yieldable take-up ram and a stationary ram surrounding the take-up ram, said take-up ram being axially yieldable relative to said stationary ram and extending thereabove; combining said body member, said deformable member, said take-up ram and said stationary ram so that the outer periphery of the inner face of said deformable member will engage said stationary ram and the take-up ram will engage the central portion of said face of said deformable member, said outer peripheries of said stationary ram and deformable member being contiguous the wall of said bore; applying pressure to said deformable member at the other face with said yieldable take-up ram and stationary ram supporting said deformable element thereby expanding the outer periphery of said deformable member into frictional fit with said bore.

6. A process for securing two members together comprising the steps of: providing a body member having a bore therein whose longitudinal dimensions extend from one surface to another, a groove in the wall of said bore; providing a deformable member whose central portion is axially offset from its outer periphery; the portion of said deformable member located between said central portion and said outer periphery being inclined to the axis of said deformable member in a direction, extending from said central portion to said periphery, which is away from said axis; providing a yieldable take-up ram and a stationary ram surrounding the take-up ram, said take-up ram being axially yieldable relative to said stationary ram and extending thereabove; combining said body member, said deformable member, said take-up ram and said stationary ram so that the outer periphery of the inner face of said deformable member will engage said stationary ram and the take-up ram will engage the central portion of said face of said deformable member, said outer periphery of said deformable member being contiguous said groove, the outer periphery of said stationary ram being contiguous the wall of said bore; applying pressure to said deformable member at the other face with said yieldable take-up ram and stationary ram supporting said deformable element thereby expanding the outer periphery of said deformable member into said groove.

7. A process for securing two members together comprising the steps of: providing a body member having a bore therein whose longitudinal dimensions extend from one surface to another, a groove in the wall of said bore; providing a deformable member whose central portion is axially offset from its outer periphery; the portion of said deformable member located between said central portion and said outer periphery being inclined to the axis of said deformable member in a direction, extending from said central portion to said periphery, which is away from said axis; providing a take-up ram and a stationary ram surrounding the take-up ram, said take-up ram being axially yieldable relative to said stationary ram and extending thereabove; placing said deformable member on said take-up and stationary rams with the inner face of the central portion of said deformable member engaging the take-up ram and the inner face of the outer

periphery of said deformable member engaging the stationary ram; placing said body member over the stationary ram, the take-up ram, and said deformable member so that the outer periphery of said deformable member will be contiguous said groove and the outer periphery of said stationary ram will be contiguous the wall of said bore; and applying pressure to said deformable member at the other face with said yieldable take-up ram and stationary ram supporting said deformable member thereby expanding the outer periphery of said deformable member into said groove.
